BRACKET FOR CURTAINS AND
DRAPERIES

James Leonard Golding and Irwin C. Bowman, Chicago, and William H. Comerford, Bellwood, Ill., assignors to J. Leonard Golding, Evelyn L. Golding, and Ann Golding, doing business as Plasti-Glo Manufacturing Company, a partnership

Application July 11, 1946, Serial No. 682,874

6 Claims. (CL 211—89)

1

This invention relates to a bracket for attachment to window frame or wall, and more particularly, refers to a bracket which, when associated with draperies or curtains, will cause them to assume a pleated position.

One object of this invention is to provide a simple, easy method of draping curtains or draperies in uniform folds by means of a bracket having spaced slots to receive said folds.

Another object of this invention is to provide a bracket capable of receiving folds of draperies and curtains of varying thicknesses and maintaining said folds under constant tension.

A further object of this invention is to provide a bracket capable of being readily positioned at a forty-five degree angle to facilitate draping continuous curtains or draperies around a window frame.

In the figures on Sheets 1 and 2, identical letters and numerals indicate like parts.

Referring to the drawing.

Fig. 1 is a perspective view showing a complete assembly of the drapery associated with two brackets permanently attached to the window frame.

Fig. 2 is a plan view of the bracket.

Fig. 3 is a front sectional view of the bracket taken along the line 3—3 of Fig. 2.

Fig. 4 is a front elevational view of the bracket attached to the window frame.

Fig. 5 is a section view of the bracket taken on line 5—5 of Fig. 2.

Fig. 6 is a perspective view of a portion of the assembly of draperies and bracket with a decorative member.

Fig. 7 is a plan view of a section of the bracket with decorative member attached thereto.

Referring to Fig. 1 of the drawing, 1 designates the window frame to which brackets 2 are permanently attached at the top corners thereof and are disposed at an angle of forty-five degrees to the horizontal plane. Associated with brackets 2 is drapery 3 inserted in slots of bracket 2, more fully illustrated in Fig. 2 to form uniform folds surrounding window frame 1.

Fig. 2 illustrates in detail bracket 2 with a series of fingers 4, preferably made of metal of approximately thirteen gauge wire, the ends of which are inserted between two parallel bars 5. The fingers 4 are adjacent each other and spaced to provide interstices 6, into which the folds of the draperies are inserted. Only one prong 7 of each finger 4 is rigidly fastened to the lower bar 8. The other prong 8 of finger 4 is unattached to parallel bars 5, thereby providing a flexible

member having spring effect, which will give when folds of curtains or draperies are inserted. The prongs 7 and 8 of fingers 4 are crinkled so as to provide several points of contact 18 with each other. The arrangement of prongs 7 and 8 are such that one rigid prong 7 and one unattached prong 8 is disposed on opposite sides of interstices 6. It will thus be seen that the combination of prongs 7 and 8 serve the dual function of allowing flexibility for the insertion of various sizes of curtains and draperies, and simultaneously provide tension on said folds of draperies, so as to maintain them in position and prevent slipping or loosening. The tension is not sufficiently great to bind, and thus, allows the user to make any adjustment desirable in arranging the folds with ease. One end of the parallel bar 5 has permanently attached to it a member 9, constructed of thicker metal, preferably 11 gauge wire, which is parallel and adjacent to flexible prong 8. Said member 9 has a function of providing aperture 10 for the insertion of drapery material, as well as means for detachably mounting decorative member, more fully illustrated in Figs. 6 and 7. At the opposite end 15 of parallel bars 5, extending rearwardly and parallel with fingers 4 is spacer member 11. Member 11 provides a means for holding in place the top end of the draperies or curtains. Eyelet 12 on member 11 may be used to secure the top 20 end of the drapery or curtain. Permanently fastened in the center of parallel bar frame 5 is a slotted plate 13, extending rearwardly and on a horizontal plane with bars 5, to which is 25 slidably mounted an L-shaped member 14, which is permanently fastened to the wall by means of screws 15. Slotted plate 13 may be forwardly or rearwardly extended the length of slot 11, and the bracket 2 may be firmly held in any extended position by tightening nut and bolt 16 at any point within the slot 11, thereby allowing the user to set his curtains and draperies from the wall. L-shaped member 14 has a downwardly 30 punched lug 21, which projects into slot 11, thus keeping both the slotted plate 13 and L-shaped member 14 parallel with each other. L-shaped member 14 also has an upwardly punched lug 22 to preclude a rotation of the nut on bolt 16. This can be clearly seen in Figs. 2 and 5. The adjustment can be made by a screw driver, and it is not necessary to use pliers or a wrench.

Fig. 3 is a section view on line 3—3 of Fig. 2 and illustrates in greater detail the construction of parallel bars 5 and prongs 7 and 8. Member 35 11 is of greater thickness, preferably 13 gauge

wire, than prongs 7 and 8. Member 11 and prong 7 are inserted between parallel bars 5 and are permanently affixed to the parallel bars 5, by spot welding, whereas, prongs 8 of fingers 4 are unattached and free to flex, as more fully explained heretofore.

Fig. 4 is a front elevational view of brackets 2 and illustrates the manner in which said bracket 2 is mounted on the wall. L-shaped member 14 terminates in a V-shape in such fashion that the sides 19 are at a forty-five degree angle. In many instances, it is desirable to adjust the brackets 2 to the frame, so that the fingers 4 are disposed in a plane, which is forty-five degrees from the horizontal. To eliminate the necessity of measuring this angle by means of a protractor, all that is required is to place one of the edges 19 parallel with the window frame. In most instances, all that is necessary is to place the edge 19 upon the upper vertical moulding, thereby assuring an accurate disposition of the bracket and eliminating any guess work. This also assures correct alignment of the two brackets disposed at the upper corners of the frame as illustrated in Figs. 1 and 6.

Fig. 5 is a section view of the bracket taken on line 5—5 of Fig. 2 and shows in greater detail the construction of L-shaped member 14 in co-operation with slotted plate 13. The downwardly punched lug 21 of L-shaped member 14 projects into slot 17 of plate 13, the edges of lug 21 being flush with the edges of slot 17, thereby preventing side to side motion of L-shaped member 14. Adjacent the hole provided in member 14 for nut and bolt 16 is an upwardly punched lug 22, spaced so that said lug 22 is flush with one edge of nut 16, thus preventing the rotation and loosening of nut and bolt 16 and providing a facile method of the screws adjustment by the use of only a screw driver and dispensing with pliers and a wrench. In Fig. 5 can also be seen the manner in which L-shaped member 14 is permanently attached to window frame 1 by means of screw 15. It can also be seen in Fig. 5 that the special extension of the bracket from the window frame 1 may be easily adjusted within the confines of slot 17 by screw adjustment 16.

Fig. 6 illustrates a drapery assembly with decorative member 20 with the brackets 2, thereby lending a more aesthetic appearance to the entire assembly.

In Fig. 7 can be seen the means of inserting decorative member 20 in the aperture 18 provided by the member 9 and prong 8 of finger 4. This provides a simple and expeditious means for the user to insert the decorative member 20.

While we have shown and described a few embodiments of our invention, this is illustrative only, and in no way limits the scope of our invention. Our invention is limited solely by and in the following claims, in which we wish to claim all novel features inherent therein.

We claim:

1. A bracket adapted to drape curtains and draperies which comprises two parallel spaced bars permanently fastened together, a series of crinkled U-shaped fingers disposed adjacent one another, each finger having its prongs inserted between the parallel bars with alternate prongs attached to a bar, and the other prongs unattached and free to flex, thereby having pairs of adjacent prongs consisting of one attached and one unattached in such manner that the adjacent prongs are adapted to maintain tension on drapery inserted between them, an end mem-

ber secured at one end of the bar adjacent an unattached prong and parallel to and extending forwardly in the same direction as the fingers and means for mounting said bracket on a wall.

5 2. A bracket adapted to drape curtains and draperies which comprises two parallel spaced bars permanently fastened together, a series of crinkled U-shaped fingers disposed adjacent one another, each finger having its prongs inserted 10 between the parallel bars with alternate prongs attached to a bar, and the other prongs unattached and free to flex, thereby having pairs of adjacent prongs consisting of one attached and one unattached in such manner that the adjacent prongs are adapted to maintain tension on drapery inserted between them, an end member secured at one end of the bar adjacent an unattached prong and parallel to and extending forwardly in the same direction as the fingers, 15 a spacer member secured at the other end of the bars parallel to and extending rearwardly from the direction of the fingers and means for mounting said bracket on a wall.

20 3. A bracket adapted to drape curtains and draperies which comprises two parallel spaced bars permanently fastened together, a series of crinkled U-shaped fingers disposed adjacent one another, each finger having its prongs inserted 25 between the parallel bars with alternate prongs attached to a bar, and the other prongs unattached and free to flex, thereby having pairs of adjacent prongs consisting of one attached and one unattached in such manner that the adjacent prongs are adapted to maintain tension on drapery inserted between them, a spacer member secured at the other end of the bars parallel to and extending rearwardly from the direction of the fingers and means for mounting said bracket on a wall.

30 4. A bracket, adapted to drape curtains and draperies which comprises two parallel spaced bars permanently fastened together, a series of crinkled U-shaped fingers disposed adjacent one another, each finger having its prongs inserted 35 between the parallel bars with alternate prongs attached to a bar, and the other prongs unattached and free to flex, thereby having pairs of adjacent prongs consisting of one attached and one unattached in such manner that the adjacent prongs are adapted to maintain tension on drapery inserted between them, a spacer member secured at the other end of the bars parallel to and extending rearwardly from the direction of the fingers and means for mounting said bracket on a wall.

40 5. A bracket, adapted to drape curtains and draperies which comprises two parallel spaced bars permanently fastened together, a series of crinkled U-shaped fingers disposed adjacent one another, each finger having its prongs inserted 45 between the parallel bars with alternate prongs attached to a bar, and the other prongs unattached and free to flex, thereby having pairs of adjacent prongs consisting of one attached and one unattached in such manner that the adjacent prongs are adapted to maintain tension on drapery inserted between them, an end member secured at one end of the bar adjacent an unattached prong and parallel to and extending forwardly in the same direction as the fingers, 50 a decorative member detachably mounted on said bracket by means of an extended member on said decorative member inserted between said end member and the prong adjacent thereto and means for mounting said bracket on a wall.

55 6. 5. A bracket adapted to drape curtains and draperies which comprises two parallel spaced bars permanently fastened together, a series of crinkled U-shaped fingers disposed adjacent one another, each finger having its prongs inserted 60 between the parallel bars with alternate prongs attached to a bar, and the other prongs unattached and free to flex, thereby having pairs of adjacent prongs consisting of one attached and one unattached in such manner that the adjacent prongs are adapted to maintain tension on drapery inserted between them, an end member secured at one end of the bar adjacent an unattached prong and parallel to and extending forwardly in the same direction as the fingers, 65 a decorative member detachably mounted on said bracket by means of an extended member on said decorative member inserted between said end member and the prong adjacent thereto and means for mounting said bracket on a wall.

70 7. 6. A bracket adapted to drape curtains and draperies which comprises two parallel spaced bars permanently fastened together, a series of crinkled U-shaped fingers disposed adjacent one another, each finger having its prongs inserted 75 between the parallel bars with alternate prongs attached to a bar, and the other prongs unattached and free to flex, thereby having pairs of adjacent prongs consisting of one attached and one unattached in such manner that the adjacent prongs are adapted to maintain tension on drapery inserted between them, an end member secured at one end of the bar adjacent an unattached prong and parallel to and extending forwardly in the same direction as the fingers, a spacer member secured at the other end of

5

the bars parallel to and extending rearwardly from the direction of the fingers, and means for mounting said bracket on a wall.

6. A bracket adapted to drape curtains and draperies which comprises two parallel spaced bars permanently fastened together at their ends, a series of crinkled U-shaped fingers disposed adjacent one another, each finger having its prongs inserted between the parallel bars, with alternate prongs attached to a bar, and the other prongs unattached and free to flex, thereby having pairs of adjacent prongs consisting of one attached and one unattached in such manner that the adjacent prongs are adapted to maintain tension on drapery inserted between them, 15 an end member secured at one end of the bars and parallel to and extending forwardly in the same direction as the fingers, a spacer member secured at the other end of the bars parallel to and extending rearwardly from the direction of the fingers, said spacer member terminating in an eyelet, a slotted plate attached to and extending rearwardly from the center of the bars, an L-shaped member slidably mounted to said slotted plate, said L-shaped member having a 25 downwardly punched lug projecting into the slot to prevent side to side motion, a hole in said L-shaped member through which a bolt is in-

6

serted to engage the slotted member and the L-shaped member, an upwardly punched lug adjacent the hole in said L-shaped member and flush with the nut screwed on said bolt, said L-shaped member terminating in a V-shape with both sides of the V at a forty-five degree angle, and a decorative member detachably mounted on said bracket by means of an extended member on said decorative member, inserted between 10 said end member and the prong adjacent thereto.

JAMES LEONARD GOLDING.
